7120X Samuel Bachelet
Spool Patent

The Schedule referred in these Spool Patent and making part of the same containing a description in the words of the said Samuel Bachelet himself of his improvement in the machinery for drying yarn preparatory to weaving. It is known that C. Young and Bachelet of late in the State of Maine have invented an improvement in the mode of drying yarn by which that preparatory operation in the business of weaving is greatly facilitated & that the following is a full and exact description of my said invention.

The accompanying drawing represents two vertical sections of part of the drying frame of the ordinary form. Fig. 1. being a section thereof as seen and with Fig. 2. a side view a. a. represents the yarn in its course from the drying rolls and brushes. b. the measuring rolls c. from which it is drawn as represented at c. c. and wound on to the beam d. The measuring rolls are usually made half a yard in circumference and as they revolve by the motion of the yarn a clock serves to indicate the quantity, &c. For the purpose of drying the yarn it is common to employ revolving fans running in tops of which bogs are shown at e. e. & sometimes a current of heated air is made to blow upon it. By my invention the revolving fans & the heated air are dispensed with, the yarn effectively dried without their aid. For this purpose I make my measuring rollers hollow or I use separate drying rollers forming them of gypsum or suitable substance & cause clean or heated air to be conducted thru them by means of hollow passages

in the same way in which callenders or other rollers are sometimes heated. As the mode of doing this is well known to have in the habit of condensing or using such machinery, it does not require to be described by me. Whether I consider steam as the most convenient vehicle of heat in the above apparatus it is manifest that hot water, metallic heated, or other articles may be employed to heat the measuring rollers. I do not therefore, intend to confine myself to the use of steam exclusively, but what I claim as my invention is the using of a cylinder of metal heated by steam or other wise in the usual place of the measuring roller, or in any other situation where they can be placed in contact with the yarn for the purpose of drying it instead of or in conjunction with the fire or heated air hitherto employed for that purpose and
